UNITED STATES PATENT OFFICE.

HERMANN FAEHRMANN, OF BROOKLYN, NEW YORK.

PROPELLER OR THE LIKE.

1,355,321.

Specification of Letters Patent. Patented Oct. 12, 1920.

Application filed August 2, 1918. Serial No. 247,915.

To all whom it may concern:

Be it known that I, HERMANN FAEHRMANN, a citizen of the United States, and resident of New York, borough of Brooklyn, and 5 State of New York, have invented certain new and useful Improvements in Propellers or the like, of which the following is a specification.

My invention relates to a propeller or the 10 like, and while it is of general application, it is particularly applicable for use with aeroplanes, where high speeds are required.

Propellers at the present time are commonly formed of wood, which is, of course, curved to a certain pitch. In a propeller of this character the centrifugal forces which act radially from the shaft tend to straighten out the blade, while the forces resulting 20 from the air pressure tend to bend back the blade, with the result that the speed which it is possible to attain with safety with this type of propeller is limited to a value below that which it is desirable in practice 25 to secure, and, at best, the propeller blades are frequently broken because of the strains set up by these forces.

In accordance with my invention, the propeller blade comprises a number of supporting ribs which constitute the frame-work 30 for the blade, and which extend radially outwardly from the shaft or hub in the same directions as do the centrifugal forces resulting from the rotation of the ribs, so 35 that there is not only no tendency for the ribs to become distorted because of these forces but the forces so set up actually provide the means to resist the tendency of the blade to become flat. In accordance with 40 my invention, also, the ribs are so formed as to withstand the enormous strains to which they are subjected because of such forces.

Another object of my invention is the 45 provision of means for detachably securing a single propeller blade unit to the hub.

Other features of my invention will appear from the specification, and will be more particularly pointed out in the claims.

50 My invention will best be understood by reference to the accompanying drawings, in which—

Figure 1 is a longitudinal section of a hub and shaft, with the inner ends of the 55 ribs mounted thereon.

Fig. 2 is a vertical section on the line 2—2 of Fig. 1.

Fig. 3 is a top plan view of this form of my invention, with parts in section.

Fig. 4 is a cross-section on the line 4—4 of Fig. 1.

Fig. 5 is a cross-section similar to Fig. 2, illustrating a modification of the previous form.

Fig. 6 is a section on the line 6—6 of Fig. 5.

Fig. 7 is a partial section of the same character as Fig. 1, but showing the form of my invention illustrated in Figs. 5 and 6.

Fig. 8 is an end view of a propeller embodying the preferred form of my invention, in which the propeller blades are balanced against each other, and here showing two propeller blades mounted diametrically 70 opposite each other on the shaft.

Fig. 9 is a side view of Fig. 8.

Fig. 10 is a longitudinal section through the hub and associated parts and showing parts in side elevation.

Fig. 11 is a sectional view showing the 80 preferred arrangement for securing the inner ends of the blades in position between clamping rings.

Fig. 12 is a sectional elevation on the line 12—12 of Fig. 8.

Fig. 13 is a sectional view on the line 13—13 of Fig. 8.

Fig. 14 is a view similar to Fig. 13 but showing a covering on both sides of the 90 blade.

Fig. 15 is an end view of a blade removed from the hub, and showing covering plates or webs secured to the ribs.

Fig. 16 is an end view of one of the ribs.

Fig. 17 is a side view of the same.

Fig. 18 is a view similar to Fig. 17 but showing the finger formed on its inner end extending in the opposite direction, and showing the taper in the thickness of the rib somewhat exaggerated to illustrate 95 after the invention, and

Fig. 19 is an end view of three equally spaced blades secured to the propeller shaft.

In the form of my invention shown in Figs. 1—7 the propeller shaft is provided with a single blade, suitable means being provided for counterbalancing the same. The propeller blade is mounted on a shaft 105, the end of which is tapered as at 11, and the extreme end of which is screw- 110

threaded as at 12. The hub which is mounted on the tapering end of the shaft comprises two sections 13 and 14 between which are secured clamping rings 15. The shaft 5 adjacent to the hub is provided with a shoulder 16 which engages a corresponding shoulder 17 of the hub. The end of the hub is preferably formed with a cap 18 which is provided with a central screw-threaded 10 opening 19, which engages the screw-threads 12 on the end of the shaft. The cap is secured to the hub section 14 by screws and nuts 20, 21 respectively, suitable recesses preferably being formed in the hub to receive the same. Ribs 22, constituting the supporting frame-work for the blade, are secured between the rings 15 and the hub sections, suitable recesses 28 being provided between the hub sections and the various 15 rings for the reception of the ribs. The ribs are tapered toward their outer ends and may be tapered in either width or thickness, but are preferably tapered both in width and in thickness for the purpose of 20 giving them a form which enables them to withstand the strains to which they are subjected, because of the centrifugal forces. The velocity of the outer ends of the ribs is, of course, much greater than that of the inner 25 ends, and as the centrifugal forces of a given rib rise with the square of the velocity from the inner toward the outer end, it is of the greatest importance that the outer ends of the ribs should be less in cross-section than the inner ends. A rib so formed provides the largest cross-section near the shaft or hub, where it is called upon to resist the greatest strains. At the same time, the mass at the outer end of the rib is sufficiently reduced to enable the propeller to 30 be rotated at higher speeds than have hitherto been attained and at higher speed than would be possible if the ends of the ribs were not so reduced in size and mass. The 35 inner ends of the ribs are preferably provided with fingers 23, which are received in recesses 24 formed on the inner faces of the rings 15, so that the fingers are secured in position between the rings and the shaft. 40 Registering openings 25 and 26 are preferably provided in the hub sections 13 and 14, which register with corresponding openings 27 formed in the rings 15, the opening as a whole being disposed on the side of the 45 hub adjacent to the blade. The side of the hub remote from the blade is, accordingly, heavier than the other side and acts as a counterbalance to the blade. A plate or web 29 is secured to the ribs, and in the 50 form shown in Fig. 2 this web is composed of a single piece secured to the ribs by rivets 30. The web is preferably secured to the ribs away from the hub, so that the ribs may be sprung apart and permit of the insertion 55 or removal of the inner retaining rings 15

in assembling or disassembling the propeller. The hub sections 13 and 14 are preferably secured to the adjacent rings by pins 31.

In the form of my invention shown in Figs. 5, 6 and 7 the ribs are formed integrally with rings 32, which are secured to a shaft 10^a, which is here shown as square in cross-section. The plate which is secured to the ribs is also shown as formed of three separate sections, 29^a, 29^b and 29^c, a 75 section being secured to each two adjacent ribs. Each blade unit is preferably made in sections, as shown in Figs. 5, 6 and 7, so that a blade unit may readily be detached from the hub and a section removed therefrom in order to make repairs. 80

The preferred form of my invention is shown in Figs. 8 to 18, in which the propeller blades are so mounted on the shaft as to counterbalance each other; that is, two 85 propeller blades may be mounted diametrically opposite each other, or any even number of blades similarly mounted diametrically opposite, or three blades may be mounted 120° apart, as shown in Fig. 19, or a multiple thereof may be employed. In one em- 90

bodiment of my invention the propeller blades, which I have indicated in general by the character A, are mounted on a hub 33 of known form, which is secured to the shaft 10^b. The hub is provided with an end flange 34, the opposite end of the hub being closed by a clamping member 35, which is also formed with an outwardly extending flange 34^a and has a cylindrical portion sur- 95

rounding the body portion of the hub proper. Annular rings 15^a are mounted on the hub and are clamped in position by a member here shown as a screw-threaded clamping ring 36, which engages the flange 100 34^a and which is received on a screw-threaded part on the hub. A screw-threaded cap 38 is preferably provided to cover the end of the shaft. The ribs 22^a are received in radial openings 15^b formed in annular raised 105 sections 15^c formed in the faces of the rings. The inner ends of the ribs are preferably formed with fingers 23^a bent at right angles 110 to the main portions of the ribs, the fingers being received between the rings and the hub. I have here shown the fingers on each 115

of the outer ribs extending outwardly, the fingers on the intermediate ribs extending in the same direction as that of one of the outer ribs. It is to be understood, however, 120 that all of the fingers, including both of those of the outer ribs, may extend in the same direction, though I prefer the first construction, as it enables me to reduce the thickness of that intermediate ring which 125 is adjacent to the rib whose finger is turned in the direction opposite to that of the others, and correspondingly decrease the weight of the hub. The inner ends of the ribs, which are received between the rings, are 130

preferably rectangular in cross-section, and formed with plane surfaces, in order the better to secure the ribs in position, the ribs being curved or twisted without the rings, 5 as best shown in Fig. 8, in order to obtain the desired pitch. I have shown in Figs. 8 and 9 three separate plates or webs 29^a, 29^b and 29^c, which are preferably formed of metal secured on one face of the ribs. It 10 is to be understood, however, that a greater or lesser number of ribs and corresponding covering plates may be used without departing from my invention.

The rib in the direction of advance of the 15 propeller is preferably the longest, since it carries the greatest strains, the ribs decreasing in length to the other edge of the blade. The outer ends of the long plates with the 20 long ribs also have the smallest pitch, the pitch gradually increasing toward the small blades with the short ribs.

The provision of ribs, in accordance with my invention, which taper toward their outer ends is of the utmost importance, since 25 it permits of the propeller being revolved at a high speed than it has hitherto been possible to attain. The strains developed in straight ribs at higher revolutions would be of such great magnitude as to break the 30 propeller. Curved ribs would be impracticable, since the centrifugal force would straighten the ribs when run at high speed. The provision of the taper in the ribs is, therefore, a feature of much greater importance than 35 might at first blush appear, since this feature makes the form of propeller embodying my invention commercially practicable.

In Figs. 9, 10 and 11 I have shown the section of the hub secured together by suitable bolts 40.

In some cases I find it desirable to cover both faces of the blade with plates or webs in order to increase the efficiency of the same and to add to the general appearance of the 45 blade. I have shown such a modification in Fig. 14, in which separate blade sections 41 and 42 are secured to the faces of the ribs. Furthermore, it is to be understood that a covering of a material such as fabric 50 or the like may be applied to either or both faces of the blades.

In accordance with my invention, the various blade units may separately be detached from the hub on which they are 55 mounted. This feature is of importance in transporting the blades, inasmuch as they may be packed for shipment to much better advantage when the blade units are separated. Furthermore, in case of injury to any portion of one of the blades, the blade may be removed and the injured section replaced without destroying the entire propeller, as is ordinarily the case where two propeller blades are formed in one integral member. In order to detach the blades from

the hub (referring particularly to Fig. 10), the hub and the blades secured thereto are demounted from the shaft by first removing the cap 38 and the screw-threaded clamping-ring 36. The bolts 40 are then 70 removed and the flange 34^a taken off. The annular rings 15^a may then be removed by spreading the ribs 22^a and a single blade unit thus removed from the hub. It will be 75 obvious that the pitch of the blade may be varied by the use of washers of differing thicknesses.

What I claim and desire to secure by Letters Patent of the United States is:—

1. A structure adapted for use as a propeller or for other purposes, comprising a shaft, a hub body and hub rings fitted on said shaft, ribs extending inwardly between said rings and provided with feet extending between the shaft and the said rings, 85 a blade secured to said ribs, and means for holding the hub body and the hub rings on said shafts.

2. A structure adapted for use as a propeller or for other purposes, comprising a 90 shaft, a hub body and hub rings fitted on said shaft and provided with recesses in their adjacent faces, ribs extending inwardly within said recesses and provided with feet extending between the shaft and the 95 said rings, a web secured to said ribs, and means for holding the hub body and the hub rings on said shaft.

3. A structure adapted for use as a propeller or for other purposes, comprising a 100 shaft, a hub body thereon, ribs extending into said hub body and provided with rings fitted on the shaft, and a web secured to the outer portions of said ribs.

4. A propeller comprising a hub adapted 105 to be secured to a shaft, a blade comprising a plurality of ribs, and annular spacing rings surrounding said hub for spacing said ribs longitudinally of the hub and securing the same thereto.

5. A propeller comprising a hub adapted 110 to be secured to a shaft, a blade comprising a plurality of ribs formed at their inner ends with laterally extending feet, and spacing rings surrounding the hub and said 115 feet, and disposed between the ribs for securing the blade to the hub and spacing the ribs longitudinally of the hub.

6. A propeller comprising a plurality of 120 blade units, each unit comprising a plurality of ribs adapted to be secured at their inner ends to the hub, and a covering secured to the ribs away from their inner ends, and means for securing said unit to the hub constructed and arranged to permit detachment 125 of the unit from the hub without removing said covering from said ribs.

7. A high-speed propeller, comprising a 130 plurality of blades counterbalanced against each other, each blade comprising a plu-

rality of metal ribs extending from the hub in straight lines, and each rib being wider in its plane of rotation than at right angles thereto and tapering uniformly both in width and thickness from the hub of the propeller to the end of the rib, the ribs of each blade being progressively shorter from one edge of the blade to the other edge of the blade, and a covering connected to the ribs 10 and conforming approximately on its outer edge to the lengths of the successive ribs.

8. A high speed propeller, comprising a plurality of blades counterbalanced against each other, each blade comprising a plurality of metal ribs extending from the hub in straight lines, and each rib being wider in its plane of rotation than at right angles thereto and tapering uniformly both in width and thickness from the hub of the propeller to 15 the end of the rib, the ribs of each blade being progressively shorter from the leading edge of the blade to the rear of the blade, and a covering connected to the ribs and conforming approximately on its outer edge to the lengths of the successive ribs.

9. A high speed propeller, comprising a plurality of blades counterbalanced against each other, each blade comprising a plurality of metal ribs extending from the hub in straight lines, and each rib being wider in 20

its plane of rotation than at right angles thereto and tapering uniformly both in width and thickness from the hub of the propeller to the end of the rib, the ribs of each blade being progressively shorter from the leading edge of the blade to the rear of the blade, and the ribs of each blade being spaced along the hub with the longest rib 25 toward the front of the hub, and a covering connected to the ribs and conforming approximately on its outer edge to the lengths of the successive ribs.

10. A high-speed propeller comprising a plurality of metal ribs extending outwardly from the hub in straight lines at their centers, each rib being wider in its plane of rotation than at right angles thereto, one side of the cross-section of a rib being a straight line and the other side a curved line, the inclination of each rib being greatest near the hub and diminishing toward the outer end of the rib.

In testimony whereof I have hereunto signed my name in the presence of two subscribing witnesses.

HERMANN FAEHRMANN.
